UNITED STATES PATENT OFFICE

2,173,049

INSECTICIDE DISTRIBUTOR

William C. Watson, Franklin, Va.

Application February 20, 1939, Serial No. 257,495

7 Claims. (Cl. 299—101)

My invention relates to insecticide distributors.

An important object of my invention is the provision of an insecticide distributor that may be manually carried and operated.

5 Another object of my invention is the provision of an insecticide distributor that will simultaneously spray adjacent rows of plants.

Still another object of my invention is to provide an insecticide distributor that is adapted to 10 thoroughly spray a row of vegetation, even though the plants are rambling or bushy in form.

Yet another object of my invention is the provision of an insecticide distributor that is efficient in operation, simple in construction, and inexpensive to manufacture.

Other objects and advantages of my invention will be apparent during the course of the following description.

In the drawing, forming a part of this specification, and in which like numerals are employed to designate like parts throughout the same,

Fig. 1 is a side elevation of a device embodying my invention.

Fig. 2 is a transverse sectional view taken on the line 2—2 of Fig. 1.

Fig. 3 is a fragmentary front elevation of the distributing pan embodying a part of my invention.

Fig. 4 is a bottom plan view of the valve controlled discharge opening of the nozzle.

Fig. 5 is a side elevation of the same.

Fig. 6 is a side elevation, showing parts broken away, of the fluid-receiving receptacle comprising a feature of my invention, and

Fig. 7 is a vertical sectional view taken on the line 7—7 of Fig. 1.

In the accompanying drawing, wherein for the purpose of illustration, is shown a preferred embodiment of my invention, the numeral 10 designates an elongated cylindrical handle member.

The numeral 11 designates a fluid-receiving receptacle formed with an inner water-tight compartment 12, of rubber or the like, having a close-fitting outer covering 13, of any suitable fabric. The top of the receptacle is provided with an upwardly extending neck 14 through

45 which the insecticide may be introduced into the receptacle. Straps 16 and 17 are secured to the sides of the receptacle and are of sufficient length to permit the same to be suspended from the shoulder of a person. The free ends of the straps are joined by a buckle 18 which permits the same to be adjusted to suit the carrier. A

50 discharge nozzle 19 depends from the bottom of the inner compartment 12 through an opening

20 in the outer covering 13, and has attached to the end thereof one end of a flexible tubing 21, the other end of which is attached to the arcuately formed nozzle 22. The nozzle 22 is securely positioned to the lower end of the handle member 10 by means of the clamp 23.

The numeral 24 designates a substantially U-shaped clamp, one arm of which is formed with an upwardly turned flange 25. The tubular member 21 passes through an opening in the closed end of the clamp and through an aligning opening in the vertically disposed flange 25. The arms of the clamps are formed with convexities intermediate their ends, and the free arm 26 is adapted to engage the opening in the flange 25 in a manner whereby the convexities in the arms will compress opposite sides of the flexible tube in a manner to check the flow of a liquid therethrough.

The discharge end of the nozzle 22 is formed with a laterally extending web 28 to which a valve plate 29 is pivotally mounted. The pivoted end of the valve plate has a right-angularly disposed arm 30, and attached to the extremity thereof is a tie element 31 which connects the said arm to a manually actuated lever member 32 which is pivotally secured to the handle 10 at substantially its middle by the clamp 33. The nozzle 22 is formed with a boss 34 at substantially right angles to the pivoted portion of the plate 28. The boss is provided with a screw threaded opening to receive the adjusting screw 35, the inner end of which bears against the side of the valve plate 29 to effectively position same in a manner whereby the size of the discharged opening may be selectively adjusted. A spring 30' is attached to the web 28 and has one end permanently seated on the boss 34, and the other end thereof engages the valve plate 29 to hold the same frictionally engaged with the adjusting screw 35.

A pan 35' is suspended from the lower end of the handle 10 by four tie elements 36, 37, 38, and 39. Rings 40 and 41 are loosely mounted on the lower end of the handle 10, one above and one below the clamp 23, and are secured in the properly adjusted position by means of the staples 42 and 43. The tie members 36 and 37, on one side of the pan, are fastened to the rings 40 and 41 respectively, and the tie elements 38 and 39, on the other side of the said pan, are attached to the staples 42 and 43 respectively. The pan 35' is of substantially trapezoidal formation in plan, and has the sides and the smaller end formed with vertical side walls, and with the

larger end 44 open to permit the insecticide to be discharged therefrom. As illustrated in Fig. 1, the pan 35' is positioned directly below the discharge nozzle 22, and with the open end 41 lower than the closed rear end 41'. The bottom of the pan is corrugated, said corrugation being outwardly divergent so that when the insecticide is discharged from the nozzle 22 into the pan 35', the liquid will be evenly dispersed to the open side 41.

10 A plurality of adjoining strips 42 are fastened to the underside of the open end 41 of the pan by the transversely extending bar 43. The strips 42 are made of any flexible material such as rubber, leather, or the like, and each of these strips is provided with a longitudinally extending groove 43' to conduct the fluid overflowing from the open end 41 of the pan downwardly and onto the plants to be sprayed.

20 The operation of my device is as follows:

In order to obtain the best results, I have found it desirable to carry two of the devices, one in the right hand and one in the left hand, and with a receptacle 11 suspended from each shoulder. In the spraying of the plants, the operator walks between the adjacent rows, with a handle member 10 grasped in either hand, and with the upper end thereof supported under the arm. The adjusting screw 35 is threaded into engagement with the valve plate 29 to move the said plate laterally across the discharge end of the nozzle and to regulate the size of the discharge opening. Once the valve plate is set to define the desired size discharge opening, its movement in a direction to close the discharge opening will be limited by the set screw and the insecticide will flow from the nozzle in a regular even manner. The fingers of the operator grasp the lever 32 and by actuating the same, the valve plate 29 may be further moved laterally of the discharge end of the nozzle to increase the size of the discharge opening. The manual control is thus used to increase the size of the discharge opening when the operator desires to apply an extra amount of the insecticide to a particular plant or section of plants and it is adapted to cooperate with the set screw in regulating the size of the discharge opening and in accordance with the particular type of plant or plants to be sprayed. When the clamp 24 is open and the valve plate 22 set to define the desired size, discharge opening, the insecticide will flow from the receptacles 11 through the tubular members 31 and be discharged from the nozzle 22 into the pan 35 where it will follow the corrugations in the bottom of the pan and flow downwardly along the grooves 43 of the strips 42. The strips 42 are flexible in their nature, and may be brushed along the plants without damaging the same. Due to this flexibility of the strips, they will drag along the top of the plants in a manner to cause the insecticide overflowing from the pan to thoroughly cover all parts of the plant. While walking between the rows of plants, the operator may manually rotate the handle 10 first in one direction and then in the other in a manner to cause the pan 35 to be tipped first in one direction and then in the other. This will cause the strips to engage the plant first from one side and then from the other side, to thoroughly cover all the branches and leaves with the insecticide.

It is to be understood that the form of my invention herewith shown and described is to be taken as a preferred example of the same, and the various changes in the size, shape, and

arrangement of parts may be resorted to without departing from the spirit of my invention, or the scope of the appended claims.

Having thus described my invention, I claim:

1. A fluid distributor comprising a support, a receptacle, a tubular element communicating with the said receptacle at one end and having the discharge end thereof secured to the support, a spring actuated valve plate pivoted to the tubular element to cover the discharge opening, a lever carried by the support and connected to the valve plate to move the same away from the discharge opening, and a pan having a corrugated bottom suspended from the body member, and under the discharge opening of the said tubular element, said corrugations being outwardly divergent to evenly spread the fluid issuing from the discharge opening.

2. A fluid distributor comprising a support, a receptacle, a tubular element communicating with the said receptacle at one end and having the discharge end thereof secured to the support, a spring actuated valve plate pivoted to the tubular element to cover the discharge opening, a lever carried by the body member and connected to the valve plate to provide for manual actuation of the same away from the discharge opening, and an adjustable stop element carried by the tubular element and engaging the valve plate to regulate the extent of closing movement of the valve plate and a pan having a corrugated bottom suspended from the body member, said corrugations being outwardly divergent to evenly spread the fluid issuing from the discharge opening.

3. A fluid distributor comprising a body member, a receptacle, a tubular element communicating with the said receptacle at one end and having the discharge end thereof secured to the body member, a spring actuated valve plate pivoted to the tubular element to cover the discharge opening, a lever carried by the body member and connected to the valve plate to move the same away from the discharge opening, a pan having a corrugated bottom suspended from the body member, said corrugations being outwardly divergent to evenly spread the fluid issuing from the discharge opening, and a plurality of adjoining strips depending from the forward end of the pan, each of the said strips having a longitudinal groove in its outer face to direct the fluid flowing from the pan.

4. A fluid distributor comprising a body member, a receptacle, a tubular element communicating with the said receptacle at one end and having the discharge end thereof secured to the body member, a spring actuated valve plate pivoted to the tubular element to cover the discharge opening, a lever carried by the body member and connected to the valve plate to provide for manual actuation of the same away from the discharge opening, an adjustable means carried by the tubular element and engaging the valve plate to regulate the extent of closing movement of the said valve plate, a pan having a corrugated bottom suspended from the body member, said corrugations being outwardly divergent to evenly spread the fluid issuing from the discharge opening, and a plurality of adjoining strips depending from the forward end of the pan.

5. A fluid distributor comprising a receptacle, a handle member, a tubular element communicating with the receptacle and having the discharge end thereof attached to the lower end of the handle member, a manually actuated valve

plate pivotally attached to the tubular member to move laterally across the discharge opening of the tubular member, and an adjustable stop element carried by the tubular element and engaging the valve plate to regulate the extent of the closing movement of the said valve plate.

5. A fluid distributor comprising a receptacle, means to support the receptacle on the body of the operator, a handle member, a tubular element communicating with the receptacle and having the discharge end thereof attached to the lower end of the handle member, a manually actuated valve plate pivotally attached to the tubular member to move laterally across the discharge opening of the tubular member, an adjustable stop element carried by the tubular element and engaging the valve plate to regulate the extent of the closing movement of the said valve plate, and a substantially square pan having an open side and a corrugated bottom suspended from the support and under the discharge opening of the tubular element, said corrugations being outwardly divergent, and flexible strips depending from the open side of the said pan and having longitudinal grooves therein to effectively direct the fluid flow-

10. A fluid distributor comprising a receptacle, means to support the receptacle on the body of the operator, a handle member, a tubular element communicating with the receptacle and having the discharge end thereof attached to the lower end of the handle member, a manually actuated valve plate pivotally attached to the tubular member to move laterally across the discharge opening of the tubular member, an adjustable stop element carried by the tubular element and engaging the valve plate to regulate the extent of the closing movement of the said valve plate, a substantially square pan having an open side and a corrugated bottom suspended from the support and under the discharge opening of the tubular element, said corrugations being outwardly divergent, and flexible strips depending from the open side of the said pan and having longitudinal grooves therein to effectively direct the fluid flow-

15. A fluid distributor comprising a receptacle, means to support the receptacle on the body of the operator, a handle member, a tubular element communicating with the receptacle and having the discharge end thereof attached to the lower end of the handle member, a manually actuated valve plate pivotally attached to the tubular member to move laterally across the discharge opening of the tubular member, an adjustable stop element carried by the tubular element and engaging the valve plate to regulate the extent of the closing movement of the said valve plate, a substantially square pan having an open side and a corrugated bottom suspended from the support and under the discharge opening of the tubular element, said corrugations being outwardly divergent, and flexible strips depending from the open side of the said pan and having longitudinal grooves therein to effectively direct the fluid flow-

20. A fluid distributor comprising a receptacle, means to support the receptacle on the body of the operator, a handle member, a tubular element communicating with the receptacle and having the discharge end thereof attached to the lower end of the handle member, a manually actuated valve plate pivotally attached to the tubular member to move laterally across the discharge opening of the tubular member, an adjustable stop element carried by the tubular element and engaging the valve plate to regulate the extent of the closing movement of the said valve plate, a substantially square pan having an open side and a corrugated bottom suspended from the support and under the discharge opening of the tubular element, said corrugations being outwardly divergent, and flexible strips depending from the open side of the said pan and having longitudinal grooves therein to effectively direct the fluid flow-
